WELL TOOL

Ora A. Brown, South Gate, Calif., assignor to
 Baash-Ross Tool Company, Los Angeles, Calif.,
 a corporation of California

Application April 5, 1938, Serial No. 200,167

13 Claims. (Cl. 164—9.7)

This invention relates to equipment and tools useful in wells and relates more particularly to a tool useful in cutting tubular objects in wells and for removing the freed or cut-off portions of such objects from the wells. A general object of this invention is to provide a tool of the character referred to that is efficient and dependable in operation and that may be operated without danger of becoming caught in the well.

10 In well drilling and producing operations it is often necessary to remove a pipe, tubing, casing and the like from a well. In many instances a tubular object of the character referred to becomes caught or sanded in the well, making 15 it impossible to remove the same bodily or as a unit. When this occurs it is necessary to cut free an upper portion of the caught tubular object, removing the said freed upper portion from the well and repeat these operations until the entire object has been recovered from the well. In carrying out this procedure it has usually been necessary to first run in a casing cutter to make a 20 cut in the tubular object, then remove the casing cutter from the well and run in a spear or the like to grip the cut free portion of the object and then pull the spear and the freed portion of the object from the well. These successive round trips of the cutter and spear into and out of the well on a sectional operating string of great 25 length that is assembled and taken apart for each run are very time consuming and therefore expensive.

Another object of this invention is to provide a tool that is operable to cut free a portion of a tubular object in a well and then grip or engage the cut free portion for removal from the well whereby the cutting operation, the grappling operation and the removing operation may be carried out during a single round trip of the operating string carrying the tool.

40 Another object of this invention is to provide a tool of the character mentioned which is adapted to be run into a well on an operating string and that is operable to cut free and then engage and support a plurality of sections of a tubular object in the well to recover said plurality of sections during a single trip of the operating string and the tool into and out of the well.

50 Another object of this invention is to provide a tool of the character mentioned that is controllable to be released from the caught object at will and therefore cannot be caught or stuck in the tubular object in the well.

55 Another object of this invention is to provide

a tool of the character mentioned that embodies means for effecting the positive connection of the control elements of body the cutting means and the object gripping means with the operating string whereby the cutting means and the gripping means are under the full control of the operator at all times.

A further object of this invention is to provide a tool of the character referred to that is easy to operate, being readily controlled from the top of the well by simple manipulation of the operating string.

The various objects and features of my invention will be fully understood from the following detailed description of a typical preferred form and application of my invention, throughout which description reference is made to the accompanying drawings, in which:

Fig. 1 is a side elevation of the tool provided by this invention showing the same being run into a tubular object in a typical well. Fig. 2 is an enlarged side elevation of the gripping means of the tool showing a portion of the connecting means in longitudinal cross section and illustrating the parts in a normal or released condition. Fig. 3 is an enlarged longitudinal detailed sectional view of the lower portion of the connecting means. Fig. 4 is an enlarged side elevation of the cutting means of the tool in operation in a tubular object illustrating the tubular object and the tailpiece in longitudinal cross section. Fig. 5 is an enlarged transverse detailed sectional view taken as indicated by line 5—5 on Fig. 2. Fig. 6 is an enlarged side elevation of the upper portion of the connecting means with the outer sleeve member removed. Fig. 7 is an enlarged transverse detailed sectional view taken as indicated by line 7—7 on Fig. 3. Fig. 8 is a diagrammatic view of the tool in position in a tubular object showing the gripping elements of both the cutting means and the gripping means actuated. Fig. 9 is a view similar to Fig. 8 showing the connecting means full contracted. Fig. 10 is a view similar to Fig. 9 showing the gripping elements of the gripping means fully retracted. Fig. 11 is a side elevation of the mandrel of the connecting means removed from the tool. Fig. 12 is a longitudinal sectional view of one of the clutch elements removed from the tool and Fig. 13 is a longitudinal detailed sectional view taken as indicated by line 13—13 on Fig. 4.

The well tool provided by the present invention includes, generally, a cutting assembly or cutting means operable to cut through the wall of a tubular object O in a well W, gripping

means 11 connected with an operating string S and operable to grip and support a cut free portion of the object O, and means 12 connecting the cutting means 10 and the gripping means 11 whereby the same may be individually controlled and manipulated by the operating string S.

The cutting means 10 is provided to make an annular cut through the wall of the object O to free or cut loose a portion of the object for removal from the well W. The cutting means 10 is connected with the operating string S through the medium of the connecting means 12 and the gripping means 11 to be supported and operated by the string. While the cutting means embodied in the tool may be varied somewhat without departing from the invention, it is preferred to employ a type of cutting means that is adapted to enter the tubular object O and that is operable to cut out through the wall of the tubular object. In the drawings I have shown a form of cutting means 10 that is controlled by movement or manipulation of the string S and that is operated by rotation of the string S to cut outwardly through the wall of the tubular object O.

The cutting means 10 illustrated in the drawings includes an elongate tubular body 13 provided at its lower end with a guide nut 14. A sub or coupling member 15 is provided on the upper end of the body 13. A collar 16 is fixed to the body 13 and spaced knives 17 are pivoted in slots in the collar 16. A cage 18 is slidable or movable with respect to the body 13 and has slots 19 through which the knives 17 project. A sleeve 20 is slidable on the body 13 and extends downwardly over the collar 16 to normally or initially cooperate with the knives 17 to hold the same retracted. The lower end of the sleeve 20 engages against the upper end of the cage 18. A spring 21 surrounds the body 13 and is under compression between the coupling member 15 and the sleeve 20 to yieldingly hold the sleeve 20 in its down position in cooperation with the knives 17. A fluid passage 9 extends longitudinally through the body 13.

The control for the knives 17 of the cutting means 10 includes a slip assembly. The slip assembly comprises a sleeve 22 shiftable on the body 13 and circumferentially spaced slips 23 cooperating with the sleeve. The sleeve 22 has downwardly and inwardly inclined surfaces 24 and the slips 23 cooperate with these surfaces. A suitable anti-friction thrust bearing 25 surrounds the body 13 between the upper end of the sleeve 22 and the lower end of the cage 18. Reins 26 extend downwardly from the slips 23 and are secured to a shiftable ring 27 surrounding the body 13.

A tailpiece controls the slips 23. The tailpiece comprises a tubular shell or sleeve 28 on the body 13 and outwardly bowed leaf springs 29 on the sleeve 28 for frictionally cooperating with the interior of the tubular object O. The upper end of the tailpiece sleeve 28 cooperates with the ring 27 associated with the slips 23. A socket 30 is provided in the lower end of the sleeve 28 and a complementary boss 31 is provided on the upper end of the nut 14. The boss 31 is initially or normally threaded in the socket 30 to releasably hold the tailpiece sleeve 28 in a down position with respect to the body 13 so that the slips 23 are released or inoperative. Helical faces 32 and axial shoulders 33 are provided on the nut 14 and the lower end of the sleeve 28 to limit the threading of the boss 31 into the socket 30 so that the

boss is always readily unthreaded from the socket.

The operation of the cutting means 10 described above is as follows. Assuming that the cutting means 10 is in a position in the tubular object O where a cut is to be made the body 13 is first rotated to the right by means of the string S as will be subsequently described. This rotation of the body 13 unthreads the boss 31 from the socket 30. The springs 29 cooperating with the object O resist turning movement of the sleeve 28 during the unthreading of the boss 31 from the socket 30. Following the threading of the boss 31 from the socket 30 the body 13 is moved downwardly. The springs 29 cooperating with the object O resist downward movement of the sleeve 28 and as the ring 27 engages against the upper end of the sleeve 28 the slips 23 are held against downward movement. The downwardly moving inclined surfaces 24 of the sleeve 22 actuate the slips 23 or force them outwardly into gripping cooperation with the interior of the object O. Continued downward movement of the body 13 after the setting of the slips 23 results in downward movement of the collar 16 and the knives 17 relative to the cage 18, the cage being held against such movement by the slips 23 through the medium of the bearing 25 and the sleeve 22. The knives 17 moving downwardly relative to the cage 18 are pivoted outwardly through cooperation with the slots 19 and thus come into cutting cooperation with the internal surfaces of the object O. The body 13 is rotated while the knives 17 are fed outwardly so that the knives 17 make an annular cut C through the wall of the tubular object O. When the knives 17 have cut through the wall of the tubular object O the body 13 revolves with less resistance, indicating to the operator that the cut C has been completed. The body 13 is then raised to retract the knives 17 and the slips 23 and to bring the boss 31 to the socket 30. The body 13 is then turned to the left to thread the boss 31 into the socket 30. The cutting means 10 is then in a retracted or inoperative condition ready to be shifted or relocated for another cutting operation.

The gripping means 11 is provided to grip and support the object O or cut free portions of the object O so that the same may be withdrawn from the well W on the string S. The means 11 is carried by the string S and is preferably of a type that is adapted to enter the object O and to grip outwardly against its interior. The form of gripping means 11 illustrated in the drawings includes an elongate body 36. The upper end of the body 36 is connected with the lower end of the string S by a suitable tool joint 37, or the like. An enlargement or head 38 is provided on the upper portion of the body 36 and has spaced longitudinal series of downwardly and outwardly inclined faces 39. Slips 40 are shiftable on the faces 39 and are operable thereby to grip outwardly against the interior of the object O. The slips 40 are toothed to be effective in transmitting lifting forces to the object O.

Dove-tailed stems 41 are provided on the upper ends of the slips 40 and are shiftable in dove-tailed grooves 42 in the head 38. Dove-tailed fingers 43 are provided on the lower ends of the slips 40 and slide in correspondingly shaped grooves 44 in the head 38. A ring 45 is shiftable on the body 36 below its head 38 and the fingers 43 have inverted T heads 46 cooperating with correspondingly shaped openings 47 in the ring 45. The heads 46 cooperating with the openings 47 connect the several slips 40 with the ring 45 so

that movement of the ring results in movement of the slips along the inclined faces 39.

The gripping means 11 includes a tailpiece for controlling the slips 40. This tailpiece includes a sleeve 48 shiftable and slidably on the body 36. Outwardly bowed springs 49 are carried by the sleeve 48 and are adapted to frictionally cooperate with the internal surface of the object O to resist movement of the sleeve 48. Steeply pitched double threads 50 are cut in the lower portion of the body 36 and the lower part of the tailpiece sleeve 48 has inturned lugs 51 cooperating with the threads 50. The threads 50 are such that turning of the body 36 to the left relative to the sleeve 48 causes the lugs 51 to move the tailpiece sleeve 48 downwardly with respect to the body 36. The threads 50 are sufficiently steep so that the lugs 51 may be moved through or caused to thread through the threads by axial movement 20 of the body 36 when its tailpiece is in cooperation with the object O. The threads 50 terminate at their upper ends at flat upper walls 52 and the threads are provided with substantially horizontal upwardly facing lower walls or shoulders 53 spaced below the walls 52. When the slips 40 are in the retracted positions illustrated in Figs. 1 and 2 of the drawings the lugs 51 seat on the shoulders 53. Short rounded projections 54 are provided at the shoulders 53 to normally retain 30 the lugs 51 in cooperation with the shoulders. The body 36 is provided with a central longitudinal opening 55 which communicates with the lower end of the string S and which extends downwardly to the lower end of the body.

35 The operation of the gripping means 11 is as follows. Assuming that the slips 41 are retracted and that the means 11 is within the object O in the well, the means 11 may be operated to grip the object by lowering the string S a short distance and then turning the string to the left. The downward movement of the body 36 moves the projections 54 out of the paths of the lugs 51 and the rotation of the body 36 to the left causes the lugs to thread or spiral down the threads 50. 40 The down-threading of the lugs 51 in the threads 50 is accompanied by downward movement of the sleeve 48 and the slips 40. If desired the body 36 may be turned to the left and moved upwardly or may be moved upwardly without being turned 45 to the left to effect the down-threading of the lugs 51 through the threads 50 as just described. It will be understood that the above-mentioned movements may be imparted to the body 36 by means of the string S extending to the ground 50 surface. Downward threading of the lugs 51 in or through the threads 50 as described above moves the slips 40 downwardly on the inclined faces 39 and the faces 39 force the slips outwardly into gripping cooperation with the interior of the object O. An up-pull may then be put on the body 36 through the medium of the string S and this up-pull is transmitted to the object O by the slips 40 so that the object O or a freed portion of the same may be raised or removed 55 from the well W.

60 The means 11 may be released from the object O when in the well by turning the body 36 to the right or by moving the body 36 downwardly, or both. Either or both of these movements cause the lugs 51 to thread or move upwardly through the threads 50 so that the sleeve 48 shifts upwardly relative to the body 36. This upward movement of the sleeve 48 with respect to the body 36 is accompanied by upward movement of

the slips 40 on the inclined faces 39 and the resultant retraction of the slips.

The means 12 for connecting the cutting means 10 and the gripping means 11 is such that the means 10 and 11 may be advantageously and successfully operated and controlled independently while in the well to carry out the desired cutting operations and the desired removal of the object O or portions of the object O. The means 12 is interposed between and connects the bodies 10 5 and 13 and 36 respectively, of the means 10 and 11. In the preferred construction illustrated the means 12 includes an elongate mandrel 56 connected with the lower end of the body 36 by a threaded connection 57. The mandrel 56 has a 15 central longitudinal opening 58 extending through it from one end to the other for conducting the circulation fluid downwardly from the opening 55.

A cylinder or tube 59 is connected with the 20 upper end of the body 13 of the cutting means 10. In practice an elongate section 60 of pipe or jointed pipe, or the like, connects the upper end of the body 13 with the lower end of the tube 59. The section 60 may be of substantial length so 25 that the means 10 is spaced some distance below the means 11. A suitable coupling member 61 may connect the lower end of the section 60 with the coupling member 15 on the body 13. A sub or connecting member 62 on the upper end of 30 the section 60 may be threaded in the lower portion of the tube 59 to connect the section 60 with the tube. A tubular plug or guide 63 is threaded in the upper end portion of the tube 59. The mandrel 56 passes downwardly through the opening 64 in the guide 63 to extend into the tube 59. A piston 65 provided with a suitable packing means is provided on the lower end of the mandrel 56 to operate in the tube 59. Thus the mandrel 56 is guided in the tube 59 at two spaced 35 points or zones, namely at the guide opening 64 and at the piston 65. The upper end of the piston 65 is cooperable with the lower end of the guide 63 to limit upward movement of the mandrel 56 relative to the tube 59.

45 Spaced grooves 66 are provided in the wall of the guide opening 64 and splines 67 are provided on the lower portion of the mandrel 56 to cooperate with the grooves. The splines 67 may be short with respect to the mandrel 56 to cooperate 50 with the grooves 66 when the mandrel is in a position where its piston 65 is at or adjacent the lower end of the guide. The splines 67 are entirely received in the grooves 66 when the piston 65 is in its uppermost position shown in Fig. 3. 55 The upper ends of the splines 67 are rounded or bevelled to readily enter the lower ends of the grooves 66. In the construction illustrated in the drawings the splines 67 have some clearance in the grooves 66 so that fluid may flow through 60 the grooves during movement of the mandrel 56 relative to the tube 59. The opening 58 of the mandrel 56 discharges into the tube 59 and the tube 59 communicates with the pipe 60 through the connecting member 62 so that fluid is delivered to the passage 9 in the body 13 of the cutting means 10.

65 The connecting means 12 includes clutch parts associated with the mandrel 56 and the tube 59 for the transmission of rotation from the mandrel to the cutting means 10 when the mandrel is in its down or lowermost position with respect to the tube 59, and clutch parts associated with the tailpiece sleeve 48 and the tube 59 to hold said sleeve from turning when the gripping slips 23 70

of the means 10 are set and the string S is turned for the purpose of retracting the gripping slips 40 of the means 11.

The connecting means 12 includes an enlargement or head 68 on the upper end of the mandrel 56. The head 68 may be cylindrical and its upper end may close the lower ends of the threads 50. The lower end of the head 68 is provided with clutch parts. In the form of the invention illustrated in the drawings two diametrically opposite notches 69 are provided in the lower end of the head 68. The wall of each notch 69 defines an axial shoulder 70 facing forwardly relative to the right hand direction of rotation and a sloping face 71 extending from the end of the head 68 upwardly to a point adjacent the base or upper end of the shoulder 70.

The means 12 further includes clutch lugs 72 on the upper end of the guide 63 for cooperating with the notches 69. The lugs 72 have vertical or axial shoulders 73 facing rearwardly relative to the right hand direction of rotation and have sloping forwardly facing edges 74. The notches 69 and the lugs 72 are related so that the lugs 25 are receivable in the notches to bring the shoulders 70 and 73 into cooperation. When the mandrel 56 is brought to its lowermost position with respect to the tube 59 and turned to the right the notches 69 receive the lugs 72 and the shoulders 30 70 and 73 engage for the transmission of forward or right hand rotation from the mandrel 56 to the tube 59. With the notches 69 and the lugs 72 in cooperation as just described, the lower end of the head 68 may cooperate with the upper 35 end of the guide 63 for the transmission of downward forces from the mandrel 56 to the guide 63 and tube 59. In the preferred construction the lugs 72 are of such width or thickness that their shoulders 73 extend outwardly beyond the peripheral surface of the head 68 when the lugs are received in the notches 69 as described above.

The connecting means 12 includes clutch parts associated with the tailpiece sleeve 48 of the means 11 for cooperating with the clutch parts 45 or lugs 72. A tube or sleeve 75 is connected with the sleeve 48 to form an extension on the lower end of the sleeve. The sleeve 75 surrounds and is shiftable and turnable with respect to the mandrel head 68. In the particular construction illustrated in the drawings a collar 76 is fixed to the lower part of the tailpiece sleeve 48 to retain the lower ends of the springs 49 in place. The invention provides a secure normally non-rotatable and readily adjustable connection between 50 the collar 76 and the sleeve 75. The lower end of the collar 76 and the upper end of the sleeve 75 have cooperating teeth 77. A downwardly facing external annular shoulder 78 is provided on the sleeve 76. A tube 79 is threaded on the 55 collar 76 and extends downwardly around the sleeve 75. An internal upwardly facing shoulder 80 is provided on the tube 79 to cooperate with the shoulder 78. When the sleeve 75 has been set in the desired rotatable position the tube 60 79 is threaded upwardly so that its shoulder 80 cooperates with the shoulder 78 to hold the teeth 77 in cooperation and thus lock the tube 75 in place. Set screws 81 may be employed to hold the tube 79 against unthreading. The sleeve 75 65 extends downwardly beyond the lower end of the tube 79.

Two diametrically opposite notches 82 are provided in the lower end of the sleeve 75 to receive or cooperate with the clutch lugs 72. The 70 notches 82 have vertical or axial walls 83 facing

forwardly to cooperate with the shoulders 73 and have sloping walls 84 extending upwardly from the lower end of the sleeve 75 to points adjacent the upper ends of the walls 83. The sleeve 75 is set or adjusted to a rotative position where the said walls 83 are in registration with the shoulders 73 of the mandrel head 68 when the slips 40 of the gripping means 11 are in their fully retracted positions. The sleeve 75 surrounds the head 68 so that its walls 83 are cooperable 10 with the outer portions of the shoulders 73 of the lugs 72.

It will be observed that the means 12 described above constitutes a slack connection between the cutting means 10 and the gripping means 11 15 and that the connecting means 12 is operable to transmit upward movement and rotation when in a fully extended condition, and is operable to transmit downward movement and rotation in a right hand direction when in a fully collapsed 20 or retracted condition. When the connecting means 12 is in an intermediate position, that is, with its piston 75 spaced between the guide 63 and the coupling member 62, the means allows free turning of the means 11 relative to the cutting means 10.

In the operation of the tool, the tool is first assembled as illustrated in the drawings and is secured to the lower end of the string S. The tool is run into the well W on the string S with 30 the parts of the cutting means 10 and the gripping means 11 in the retracted conditions illustrated in Figs. 1, 2 and 3 of the drawings. The device or tool is lowered to a position where the cutting means 10 is in the object O and is in position to 35 make a cut. As illustrated in Fig. 1 of the drawings the section 60 and the connecting means 12 may be of such length that the gripping means 11 is above the object O when the cutting means 10 is in position to make a cut, although this relationship of parts is not essential.

With the cutting means 10 in position for a cut the string S is turned to the right. With the connecting means 12 extended as shown in Figs. 1, 2 and 3 of the drawings the splines 67 cooperate 45 with the grooves 66 to transmit the rotation from the mandrel 56 to the tube 59, the section 60 and the body 13. In the event the means 12 is in its contracted condition the shoulders 70 and 73 cooperate for the transmission of the right hand 50 rotation. This right hand rotation unthreads the boss 31 from the socket 30. Right hand rotation of the string S to control and operate the cutting means 10 does not affect the gripping means 11 and the lugs 51 remain at the upper 55 ends of the threads 50. The string S is then lowered or allowed to settle and the right hand rotation of the string is continued. When the string S is lowered the weight of the body 13, the section 60, the tube 59 and the parts connected therewith may cause the body 13 to move downwardly. The springs 29 resist downward movement of the slips 23 and the inclined faces 24 on the downwardly moving body 13 actuate the slips outwardly into gripping cooperation with 65 the interior of the object O. With the slips 23 actuated, the body 13, the section 60 and the tube 59 are held against downward movement by the engagement of the slips 23 with the object, and the string S may continue to move downwardly to 70 a position where the shoulders 70 of the mandrel head 68 cooperate with the shoulders 73 of the lugs 72. The cooperation of the shoulders 70 and 73 transmits the right hand rotation to the assembly of the tube 59, the section 60 and the 75

body 13. The weight of the body 13, section 60, tube 59 and the associated parts may be sufficient to feed the knives 17 outwardly or if necessary the weight of the string S may be imposed on the tube 59 to effect the actuation of the knives 17 by downward movement of the knives relative to the cage 18, the cage being held against such movement by the slips 23. The knives 17 feed outwardly in this manner and, carried by the rotating body 13, make the annular cut C in the object O.

When the knives 17 have cut through the wall of the object O the string S is raised and turned to the left. The upward movement of the string S moves the mandrel 56 upwardly relative to the tube 59, separates the head 68 and the sleeve 75 from the clutch lugs 72 on the guide 63 and brings the splines 67 into cooperation with the grooves 66. The piston 65 may cooperate with the lower end of the guide 63 to transmit upward movement to the tube 59, the section 60 and the body 13 and this upward movement of the body 13 releases or retracts the slips 23 and brings the boss 31 up to the socket 36. The left hand rotation of the body 13 threads the boss 31 into the socket 39 so that the cutting means 10 is restored to its original retracted or inactive condition. Rotation of the string S to the left when an up strain is maintained on the string as just described, does not affect the gripping means 11 as the lugs 51 and the shoulders 53 remain in cooperation and the lugs do not pass over the projections 54. Or if the gripping means 11 is above the object O as illustrated in Fig. 1, the tailpiece springs 49 do not resist rotation of the sleeve 48 and no relative movement or turning occurs between the lugs 51 and the threads 50. Furthermore, when the means 10 is above the object O its slips 40 cannot obtain a grip on the large diameter well casing or the well wall.

The string S may then be lowered to enter the gripping means 11 into the portion of the object O freed by the cut C. With the gripping means 11 in the selected position in the freed portion of the object O the string S is moved downwardly and turned to the left. The springs 49 resist downward movement of the lugs 51 so that the projections 54 are moved out of the path of the lugs. The rotation of the string S and body 36 to the left brings the threads 50 into cooperation with the lugs 51 and the threads operate to feed or thread the lugs 51 and the tailpiece sleeve 48 downwardly. Downward movement of the tailpiece sleeve 48 is accompanied by downward movement of the slips 40 and the slips are actuated outward by the inclined faces 39 into gripping engagement with the interior of the object O.

When the slips 40 have been set or actuated the string S may be pulled from the well to release the cut-free portion of the object O. In the event that the cut-free portion of the object O is stuck or sanded in the well and cannot be pulled from the well or if for any other reason it is desired to make another cut in the object O the string S may be lowered and turned to the right to release the gripping means 11. Downward movement or downward movement and right hand rotation of the string S causes the threads 50 to cooperate with the lugs 51 to thread or feed the tailpiece sleeve 48 and the slips 40 upwardly. This upward movement of the slips 40 retracts or releases the slips. The string S may then be raised or brought to the position where it is desired to make the second cut in the object O and the above operations may be repeated.

If for any reason the lowering of the string S and the right hand turning of the string S to release the slips 40 of the means 11, preparatory to a second cut, should fail to retract the slips 40 and should cause unthreading of the boss 31 from the socket 36 downward movement and the right hand turning of the string S may be continued. The engagement of the slips 23 with the object O will arrest downward movement of the tube 59, the section 60 and the body 13 and the knives 17 may engage the object to resist turning of the body 13, section 60 and tube 59. The above manipulation of the string S therefore brings the clutch shoulders or walls 83 into cooperation with the shoulders 73 of the lugs 72. This relationship of the elements is shown diagrammatically in Fig. 9 of the drawings. The cooperation of the clutch walls 83 with the clutch shoulders 73 holds the tailpiece sleeve 48 against turning and the above-mentioned right hand rotation of the string S causes the threads 50 to cooperate with the lugs 51 to thread or feed the tailpiece sleeve 48 upwardly to retract or release the slips 40. Thus the connecting means 12 assures the positive retraction of the gripping slips 40 in the event that the same are not or cannot be retracted by the normal operation of the tool. During the right hand rotation of the string S to effect the retraction of the slips 40 while the walls 83 cooperate with the clutch shoulders 73 the clutch shoulders 70 turn and move downwardly, ultimately coming into engagement with the shoulders 73. The engagement of the shoulders 70 with the shoulders 73 occurs when the slips 40 have been freed or retracted from the object O and serves to limit relative turning between the body 36 and the tailpiece sleeve 48. The gripping means 11 is always capable of downward movement in the object O and if desired the tool may be lowered to bring the nut 14 against the bottom of the well. With the nut in engagement with the bottom of the well W the downward movement of the tube 59 is stopped and its turning is resisted so that the above described procedure results in cooperation of the shoulder 73 and the wall 83 and the means 11 is releasable in the manner just described. Following the release of the slips 40 the tool may be raised, then manipulated and controlled as described above to make another cut in the object O.

It will be understood that the tool provided by the invention is operable to make a plurality of vertically spaced cuts C in the object O to provide for the ready removal of the cut-free portions of the object from the well. If it is found that a plurality of cut-free lengths of the object O are loose and capable of being removed from the well the gripping means 11 may be run into the lowermost loose portion and actuated to grip the same. The string S may then be pulled from the well to recover the plurality of cut-free portions of the object O. Throughout the operation of the tool or during any part of the operation of the tool circulation fluid may be pumped downwardly through the string S to flow through the opening 55, the opening 58 in the mandrel 56, the tube 59, the section 60 and the opening 9 in the body 13 to discharge from the lower end of the nut 14. The fluid may be employed to prevent sanding up of the tool and flushing of the knives 17 and may be employed to assist in freeing the object O from the accumulation of sand in the well.

Having described only a typical preferred form and application of my invention I do not wish

to be limited or restricted to the specific details herein set forth, but wish to reserve to myself any variations or modifications that may appear to those skilled in the art or fall within the scope of the following claims.

Having described my invention, I claim:

1. A tool useful in removing tubular objects from wells comprising an expandible normally contracted cutting means conditioned for expansion by rotation and expanded by axial movement to make a cut through the wall of a tubular object in a well when rotated in said object, a gripping means controlled by axial movement and turning movement to grip the said object above the cut made by the cutting means, an operating string connected with one of said means, and a connecting means connecting the cutting means and the gripping means and spacing the cutting means a substantial distance below the gripping means.
2. A tool useful in removing tubular objects from wells comprising a normally contracted cutting means conditioned for expansion by rotation and expanded by axial movement to make a transverse cut through the wall of a tubular object in a well when rotated in said object, gripping means operable by axial movement and turning movement to grip said object above the cut made by the cutting means, an operating string connected with the cutting means to operate the same, and a slack connection between the gripping means and the cutting means operable to transmit rotation whereby the cutting means is operable by manipulation of the string.
3. A tool useful in removing tubular objects from wells comprising a cutting means conditioned for operation by the application of turning movement in one direction and operable by such turning movement and axial movement to cut transversely through the wall of a tubular object in a well, gripping means conditioned for operation by the application of axial force and operable by such force and a turning force in a direction opposite to said turning movement to grip the object above said cut, an operating string connected with said gripping means and manipulable to apply said forces to the same, and a slack connection between the gripping means and the cutting means operable to transmit turning movement whereby the cutting means is controllable and operable by the string through the medium of the gripping means.
4. In combination, a cutting means adapted to be entered in a tubular object in a well and comprising a body, a cutting element carried by the body to cut through the wall of the tubular object by rotation of the body, and a control for the cutting element releasable by turning of the body in one direction and axial movement of the body to condition the cutting element for operation, a gripping means adapted to be entered in said object and comprising a body, gripping elements carried by the last mentioned body and a control for the gripping elements operable by turning movement of said last mentioned body in a direction opposite to said turning of the first mentioned body to actuate the slips into gripping engagement with the object, a string connected with said last mentioned body for manipulating and operating the gripping means, and a slack connection between said bodies operable when in the contracted condition to transmit rotation whereby the cutting means is controllable and operable by the said string.
5. In combination, a cutting means adapted

to be entered in a tubular object in a well and comprising a body, a cutting element carried by the body to cut through the wall of the tubular object by rotation of the body, and a control for the cutting element releasable by turning of the body in one direction and axial movement of the body to condition the cutting element for operation, a gripping means adapted to be entered in said object and comprising a body, gripping elements carried by the last mentioned body and a control for the gripping elements including a tailpiece shiftably supported on said last mentioned body and operatively associated with the gripping elements, the tailpiece having parts cooperating with the object to yieldingly hold it against movement, and means operable by turning of the said last mentioned body in a direction of rotation and with respect to the tailpiece to move the tailpiece to actuate the slips into gripping cooperation with the object, a string connected with the said last mentioned body to operate the same, and a slack connection between said bodies operable when in the contracted condition to transmit rotation and having means for holding said tailpiece against turning whereby turning of the string in the first mentioned direction releases the gripping elements.

6. In apparatus of the character described a well string, a gripping tool adapted to be run into a tubular object in a well and including a body secured to the string, elements for gripping the object, a tailpiece shiftable on the body to expand and contract the gripping elements, thread means for effecting shifting of the tailpiece upon rotation of the body, and a control device comprising two relatively longitudinally shiftable members, one member being secured to the body, and clutch parts on the other member and the tailpiece engageable upon contraction of the members to hold the tailpiece against turning whereby the string may be rotated to actuate the thread means to retract the gripping elements.

7. In apparatus of the character described a well string, a gripping tool adapted to be run into a tubular object in a well and including a body secured to the string, elements for gripping the object, a tailpiece shiftable on the body to expand and contract the gripping elements, thread means for effecting the shifting of the tailpiece upon rotation of the body, and a control device comprising two relatively longitudinally shiftable members, one member being secured to the body, clutch parts on the other member and tailpiece cooperable upon contraction of the members to hold the tailpiece against turning movement whereby the string may be rotated to actuate the thread means to retract the gripping elements, and rotation transmitting means on said members cooperable when the members are contracted, and a cutting tool carried by said other member operable by rotation to act transversely through the wall of the said object.

8. In apparatus of the character described a well string, a gripping tool adapted to be run into a tubular object in a well and including a body secured to the string, elements for gripping the object, a tailpiece shiftable on the body to expand and contract the gripping elements, thread means for effecting the shifting of the tailpiece upon rotation of the body, and a control device comprising two relatively longitudinally shiftable members, one member being secured to the body, clutch parts on the other member and tailpiece cooperable upon contraction of the members to

hold the tailpiece against turning movement whereby the string may be rotated to actuate the thread means to retract the gripping elements, and rotation transmitting means on said members cooperable when the members are contracted, and a cutting tool carried by said other member operable by rotation to act transversely through the wall of the said object, said cutting tool comprising means for gripping the said object operable by axial movement of the cutting tool.

9. In apparatus of the character described a well string, a gripping tool adapted to be run into a tubular object in a well and including a body secured to the string, elements for gripping the object, a tailpiece shiftable on the body to expand and contract the gripping elements, thread means for effecting the shifting of the tailpiece upon rotation of the body, and a control device comprising two relatively longitudinally shiftable members, one member being secured to the body, clutch parts on the other member and tailpiece cooperable upon contraction of the members to hold the tailpiece against turning movement whereby the string may be rotated to actuate the thread means to retract the gripping elements, and rotation transmitting means on said members cooperable when the members are contracted, and a cutting tool carried by said other member operable by rotation to act transversely through the wall of the said object, said cutting tool comprising a body connected to said other member, cutting elements on the last mentioned body operable by rotation to cut through the wall of the object, and a control for the cutting elements including object gripping means operable by axial movement of the said last mentioned body.

10. In apparatus of the character described a well string, a gripping tool adapted to be run into a tubular object in a well and including a body secured to the string, elements for gripping the object, a tailpiece shiftable on the body to expand and contract the gripping elements, thread means for effecting shifting of the tailpiece upon rotation of the body, and a control device comprising two relatively longitudinally shiftable members, one member being secured to the body, means carried by the other member for engaging the said object to resist movement of said other member, rotation transmitting means on the member cooperable when the members are in contracted positions with relation to one another, and stop parts in said other member and the tailpiece cooperable when the members are thus contracted to hold the tailpiece against turning whereby the string may be turned to retract the gripping elements.

11. In apparatus of the character described a well string, a gripping tool adapted to be run into a tubular object in a well and including a body secured to the string, elements for gripping the object, a tailpiece shiftable on the body to control the gripping elements and frictionally engaging said object, thread means operable to shift the tailpiece to cause actuation or allow retraction of the gripping elements upon turning of

the body relative to the tailpiece, two telescopically related relatively shiftable and turnable members, one member connected to the body, means carried by the said other member and cooperable with the said object to hold the said other member against downward movement, and stop parts on the tailpiece and said other member cooperable when the members are in contracted positions with relation to one another to hold the tailpiece against turning whereby turning of the body causes the thread means to shift the tailpiece and thus allow retraction of the gripping elements.

12. In apparatus of the character described a well string, a gripping tool adapted to be run into a tubular object in a well and including a body secured to the string, elements for gripping the object, a tailpiece shiftable on the body to control the gripping elements and frictionally engaging said object, thread means operable to shift the tailpiece to cause actuation or allow retraction of the gripping elements upon turning of the body relative to the tailpiece, two telescopically related relatively shiftable and turnable members, one member connected to the body, the other member extending downwardly from the first member, spline means on the members cooperable when the members are in the contracted condition, means carried by the said other member and cooperable with the said object to hold said other member against downward movement, and stop parts on the tailpiece and said other member cooperable when the members are in said contracted condition to hold the tailpiece against turning whereby turning of the body actuates the thread means to move the tailpiece axially with respect to the body to allow retraction of the gripping elements.

13. In apparatus of the character described a well string, a gripping tool adapted to be run into a tubular object in a well and including a body secured to the string, elements for gripping the object, a tailpiece shiftable on the body to control the gripping elements and frictionally engaging said object, thread means operable to shift the tailpiece to cause actuation or allow retraction of the gripping elements upon turning of the body relative to the tailpiece, two telescopically related relatively shiftable and turnable members, one member connected to the body, the other member extending downwardly from the first member, spline means on the members cooperable when the members are in the contracted condition, means carried by the said other member and cooperable with the said object to hold said other member against downward movement, and stop parts on the tailpiece and said other member cooperable when the members are in said contracted condition to hold the tailpiece against turning whereby turning of the body actuates the thread means to move the tailpiece axially with respect to the body to allow retraction of the gripping elements, and stop parts on the members operate to limit turning between the members when the tailpiece reaches a position where the gripping elements are retracted.

ORA A. BROWN.
